UNITED STATES PATENT OFFICE.

ROBERT KNICKERBOCKER, OF BLUE ISLAND, ASSIGNOR OF ONE-HALF TO
CHARLES F. WARDELL, OF CHICAGO, ILLINOIS.

BRICK-MACHINE.

SPECIFICATION forming part of Letters Patent No. 431,117, dated July 1, 1890.

Application filed January 10, 1890. Serial No. 336,485. (No model.)

To all whom it may concern:

Be it known that I, ROBERT KNICKERBOCKER, a citizen of the United States, residing at Blue Island, in the county of Cook 5 and State of Illinois, have invented certain new and useful Improvements in Brick-Machines, of which the following is a specification.

My invention relates to that class of brick-machines in which is provided a rotary platen with mold-boxes therein, and having an upper and lower set of dies which rotate with the frame, and which are caused to reciprocate vertically to compress the clay within the mold-box to form the brick and likewise to eject the brick from the mold after it is pressed. In the preferred construction I provide a base having a circular cam-track on its upper surface and a stationary plate above the base, supported therefrom by suitable posts or girders, said plate having a cam-track formed on its lower side, a rotary platen having mold-boxes therein between the base and the described plate, a stationary feed-box delivering over the path of the mold-boxes, a set of upper dies secured to reciprocate in vertical ways in a frame rotatable with the platen, a set of lower dies secured to reciprocate in ways below the platen and 20 rotatable therewith, each set of dies having shanks bearing conical rolls adapted to the respective cam-tracks, an upper auxiliary cam-track on which the upper dies also have a bearing for lifting the dies at one point of their revolution, and a lower auxiliary cam-track to withdraw the lower dies in the mold-box, said lower auxiliary cam-track having a vertically-adjustable section, whereby the reciprocation of the lower dies may be varied 25 to vary the quantity of clay admitted, and removable sections in the stationary top plate and in the lower cam-track to permit of the removal of the dies. I also give the upper and lower cam-tracks a peculiar configuration, so as to impart to the upper and lower dies peculiar movements, summarized as follows: After the mold-box is filled with the clay the upper dies are caused to move downwardly and the lower dies upwardly, the initial movement of the former being more rapid 30 than that of the latter, and when the upper

die has entered the mold-box a certain distance it begins to recede while the lower die continues to ascend, the result being that the formation of the brick under pressure is completed while it is being moved upwardly in the mold-box, and when the upper die leaves the mold-box the upper surface of the brick is flush with the top of the plate, and then, both upper and lower cam-tracks being sharply inclined, the upper die is lifted clear and the lower die is moved up rapidly to eject the brick, which is removed by a suitable knock-off device. The upper and lower dies each have stems bearing conical rollers, 65 and the cam-tracks are inclined toward the center of rotation to correspond to the formation of the rollers, and thereby the lateral movement of the rollers on the cam-tracks is avoided and abrasion of their surfaces and of 70 the tracks obviated.

In the accompanying drawings, Figure 1 is a side elevation of a machine of the preferred construction. Fig. 2 is a sectional elevation, some of the parts omitted and other parts being shown entire. Fig. 3 is a plan view designed particularly to show the opening of the stationary top plate. Fig. 4 is a diagrammatic view of the upper and lower cam-tracks. Figs. 5 and 6 are detail views of the adjustable section of the lower auxiliary cam-track. 75

In the drawings, 9 represents a convenient base for the machine, on the upper surface of which is formed a circular cam-track 10, having a removable section 11 to permit the taking out and replacing of the dies. The bearing-face of this cam-track is inclined downwardly from its inner to its outer edge—that is, toward the center of movement—as clearly shown in the drawings, and for a purpose hereinafter described. Rising from the center of the frame is an integral extension of the base in the form of a column 12, which is the axis of the rotary parts. At the top of said column is secured a stationary plate 13, parallel to the base, having a removable section 13^a, Fig. 3, and on the under surface of said plate is a circular cam-track 14, whose face is inclined toward the common center of the rotating parts. 90

15 is a rotary platen having the mold-boxes 16, and which platen may be rotated by a suit-

able driving-pinion, as 17, meshing with gear-teeth 18 on the periphery of the platen.

19 is a frame, secured by the bolts 20 to rotate with the platen. In this frame are formed 5 the guides 21 for the upper dies 22, whose cross-heads move within the guides 21 and carry the conical rollers 23, which are adapted to the bearing-surfaces of the cam-track 14. The cross-heads of the upper dies will slide 10 freely in the ways, and the cam-track 14, being of the configuration shown in Fig. 4, will cause these dies at one point of the revolution (indicated at *a b*, Fig. 4) to move downward and enter the mold-box after the latter 15 has been filled. From *b* to *c* the cam-track 14 gradually rises, and the upper die will rise under pressure of the lower one until it reaches the point *c*; from whence to *d* the cam-track inclines upward sharply, thus permitting of 20 the upper die being raised to pass any obstruction of the platen, as, for example, the stationary feed-box 24. From *d* to *e* the upper cam-track may be horizontal, and the upper die may be moved in a horizontal plane to 25 pass said obstruction, after which the track declines sharply from *e* to *a*, thus causing the descent of the upper die upon the clay, which it commences to press at *a*.

The lower dies (marked 25) move in ways 30 26 and carry the conical rollers 27, which are adapted to the lower cam-track 10. The configuration of this track is shown in Fig. 4, and is of a uniform inclination from *f* to *g*. At the point *f* the clay will have been filled 35 into the mold-box, whose bottom is closed by the lower die, and which die will then move upward, no pressure being exerted, however, until the upper die has arrived at *a*. At that point the pressure of the clay between the 40 two dies commences and is constantly increased until the upper die reaches *b*, at which point the upper die begins to rise, as before described, while the lower die constantly ascends from *f* to *g*, from which latter point to 45 *h* the brick is ejected from the mold-box. From *h* to *i* the lower die may travel in a horizontal plane—that is, with its upper end flush with the face of the platen—and then it may descend by gravity; but it is preferably positively depressed by means of a lower auxiliary cam-track 28, which receives a roller 29, secured to the end of the arbor 30 of the roller 27. This auxiliary cam-track need only be 50 of such length as to act upon the lower die during its movement through a fragmentary portion of its circuit—as, for example, from *i* to *f*—and it effectually prevents any imperfection of operation caused by the clogging or sticking of the die in the mold-box. I prefer to make this section of cam-track 28 vertically adjustable, and the means whereby it is adjusted are shown in Figs. 5 and 6, in which figures the cam-track has supporting-feet 28^a, entering apertures in the base 10, which base 55 is cut away beneath the cam-track 28 to receive the wedge 31, which latter terminates in a threaded end 32, to which the adjusting-nut

33 is applied. By tightening this nut the wedge will force the track-section 28 upwardly, and when this track is reached by the roller 29 70 the die 25 will be lowered in the mold-box; but the roller 27 will be held suspended above the cam-track 10, and thus by the vertical adjustment of this track 28 the quantity of clay admitted to the mold-boxes may be regulated. 75

The clay or other material to be pressed will be fed to the molds through a stationary feed-box 24, which may be of the form shown in Fig. 1, in which the box has the hopper 24^a and the horizontal extension 24^b opening over 80 the path of the mold-boxes. Where a stationary feed-box is employed, it is essential to provide some means for raising the upper die from the feed-box, which must project inward upon the platen over the mold-box. 85 This may be done in a variety of ways; but the preferred form of construction is to employ an auxiliary cam-track 34, which may be a flanged casting bolted to the upper side of the top plate 13, and adapted to receive 90 thereon a roller 35, secured upon the arbor 36 of the rollers 23. This track may be short, as the width of the mold-box is not great; but where it is desired to lift the upper die over any obstruction on the platen—as, for 95 example, the knock-off device—the cam-track 34 will correspondingly be lengthened.

I claim—

1. In a brick-machine having a stationary base and top plate, each having integrally-formed circular cam-tracks, a revolving platen, and an upper and lower set of reciprocating dies rotatable with said platen, having bearing, respectively, on the cam-tracks of the base and top plate, and said top plate and base having removable sections to permit of the insertion and removal of the dies, substantially as described.

2. A brick-machine having an upper and lower set of reciprocating dies, a stationary base, and top plate, said base having a circular cam-track whereon the lower dies have a bearing, said cam-track extending with a uniform upward inclination throughout the greater part of its length, and having at 115 one point therein a raised portion adapted to lift the lower dies whereby to eject the brick, and said top plate having on its lower surface a circular cam-track on which the upper dies have a bearing, said cam-track 120 being inclined at one point therein toward the lower cam-track and oppositely inclined throughout a portion of its length, but at a less degree than the corresponding portion of the lower cam-track, whereby the lower 125 dies are caused to move faster than the upper dies during the act of forming the brick, substantially as described.

3. In a brick-machine, the combination of a stationary base and top plate, a rotary platen, an upper and a lower set of reciprocating dies, cam-tracks on the base and top plate on which the respective sets of dies have a bearing, and an upper auxiliary cam-

track on which the upper set of dies also have a bearing, said upper auxiliary track having a raised portion therein whereby to lift the dies at one point of their revolution, and a 5 lower auxiliary cam-track having an adjustable section, whereby said lower dies are positively depressed at one point of their revolu-

tion, and whereby their downward movement may be regulated, substantially as described.
